(57) **CLAIM**

The ornamental design for a wireless charger, as shown and described.

DESCRIPTION

FIG. 1 is a bottom, front, left side perspective view of a wireless charger, showing my new design in a closed configuration;

FIG. 2 is a bottom, front, right side perspective view of the wireless charger, shown in an open configuration;

FIG. 3 is a front view of the wireless charger shown in the closed configuration;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines in the drawings depict portions of the wireless charger that form no part of the claimed design.

1 Claim, 8 Drawing Sheets
